CRUSHER

Harvey H. Rumpel, Milwaukee, Wis., assignor to
 Smith Engineering Works, Milwaukee, Wis., a
 corporation of Wisconsin

Application February 5, 1936, Serial No. 62,464

1 Claim. (Cl. 83—10)

The present invention relates generally to improvements in the art of reducing hard substances such as rock and ore, and relates more specifically to various improvements in the construction and operation of gyratory crushers especially adapted to be utilized as reduction crushers for producing relatively coarse granular product of uniform size.

An object of the invention is to provide an improved crusher which is simple and compact in construction, and which has enormous capacity and is highly efficient in operation.

Another object of the invention is to provide a new and useful gyratory crusher assembly, of durable structure wherein the various parts are effectively protected against loosening, breakage, and entry of gritty substances.

A further object of the invention is the provision of simple and efficient means for preventing breakage of main crusher parts in case pieces of uncrushable substances of relatively large size are accidentally admitted to the crushing chamber.

Still another object of the invention is to provide improved instrumentalities for protecting the adjusting mechanisms and bearing of a crusher against ingress of dust and lack of lubricants.

An additional specific object of the invention is to provide improved concave supporting and adjusting structure for gyratory crushers or the like, and also improved head supporting and attaching mechanism.

Another object of the invention is the provision of an improved crusher driving eccentric, the internal and external bearing surfaces of which will be automatically and abundantly lubricated during normal operation of the machine.

A further object of the invention is to provide an improved gyratory crusher, the bearings of which are properly protected and lubricated at all times, and which can be manufactured and operated at minimum cost.

Still another object of the invention is the provision of improved head and concave liner attachments which are simple in construction and effective in use.

These and other objects and advantages of the invention will be apparent from the following detailed description.

A clear conception of embodiments of the several features constituting the present improvement, and of the mode of constructing and of operating gyratory crushers built in accordance with the improvement, may be had by referring to the drawing accompanying and forming a part

of this specification in which the various parts are identified by suitable reference characters.

Fig. 1 is a central vertical section through a gyratory crusher embodying the improvements;

Fig. 2 is a fragmentary transverse horizontal section through the machine, taken along the line 2—2 of Fig. 1; and

Fig. 3 is another similar section taken along the line 3—3 of Fig. 1.

While the improvements have been shown and described herein as being specifically applied to a gyratory crusher of a particular type especially adapted for reduction purposes as distinguished from primary breaking, it is not the intent to unnecessarily restrict the scope by such specific embodiment, since some of the improved features are obviously more generally applicable.

Referring to the drawing, the vertical gyratory crusher shown therein comprises in general a normally gyratable inner crushing member or head 4 carried by the upper end of a main shaft 5 and having a frusto-conical protecting mantle 6; an annular normally stationary outer crushing member or concave 7 surrounding the head 4 and having a downwardly and outwardly flaring removable annular liner 8 surrounding and overlying the head mantle 6 to form an annular downwardly extending and outwardly spreading crushing chamber 9; a stationary main frame 10 constituting a firm support for the concave 7 and liner 8; and a rotary eccentric 11 journaled in the main frame 10 and in a bearing member 12 secured to this frame, this eccentric coacting with the main shaft 5 to gyrate the head 4 and mantle 6 relative to the concave 7 and liner 8 during normal operation of the crusher.

The head 4 may be of conical formation as shown, or it may be of substantially semi-spherical form, and has a relatively rough outer surface and a central tapered bore snugly fitting the upper tapered end 13 of the shaft 5. The upper extremity of the shaft 5 is provided with an integral threaded portion 14 of reduced diameter projecting upwardly beyond the head 4, and the frusto-conical mantle 6 has its lower interior provided with an annular projection which is tapered for direct coaction with the lower end of the head 4. A retainer nut 15 has screw thread coaction with the reduced portion 14 of the main shaft 5, and coacts directly with the upper end of the mantle 6 but is spaced slightly from the head 4. The nut 15 has a top plate 16 welded thereto after threading of the nut, and also has vertical diametrically opposite through holes 17 adapted to receive a spanner wrench during ap-

plication of the nut to the shaft portion 14 and while the mantle 8 is being forced against the head 4. The holes 17 are filled with metal 18 such as zinc after the nut 15 and head 4 have been finally positioned, and this metal 18 fills the space between the nut 15 and the top of the head 4 and also extends downwardly into the annular space between the major portion of the mantle 8 and head 4 above the lower head contacting projection of the mantle. With this assemblage of elements, the mantle 8 and the nut 15 are prevented from rotating relative to the head 4, by the metal 18, and the metal 18 may be readily drilled out of the holes 17 when it is desired to release the nut 15 so as to effect removal of the mantle 8. The closure plate 16 also permits convenient threading of the nut 15 during construction thereof, and serves to protect the threads and the shaft portion 14 of the final assemblage. The lower end of the head 4 is provided with vertically offset plane bearing surfaces 19, 20 which coat with the upper extremity of the bearing member 12.

The concave 7 is provided with an internal tapered bore which is snugly engaged by an annular peripheral projection at the lower end of the liner 8, and the liner has two or more integral radial lugs 21 which are insertible through slots 21' in the concave 7 during application and removal of the liner 8, and which finally coat with upper surfaces of ledges 22 thus providing a support for the liner 8. The spaces between the concave 7 and liner 8, including the slots 21' are finally filled with metal such as zinc to finally positively lock the liner in place, and this metal may be drilled from within the slots 21', or the lugs 21 may be burned off when the liner is to be removed, and this may be done from above.

While the central axes of the liner 8 and of the head mantle 8, may be parallel, these axes are off-set so as to provide a crushing chamber 8 which is of greater width at one side of the machine than at the opposite side, as clearly indicated in Fig. 1. The annular inlet opening at the upper end of the chamber 8 is free from obstructing spider arms or the like, and the entering material may be guided into this inlet opening by a hopper wall 23 secured to the concave 7. The discharge opening at the lower end of the crushing chamber 8 is also free from obstruction, and communicates with a substantially annular delivery passage 24 formed in the main frame 18. The concave 7 is directly sustained by an annular supporting element 25 having internal screw threads 26, and which is provided with an outer upper sealing ring 27 and a lower inner sealing ring 28 disposed at opposite ends and on opposite sides of the threads 26. The lower end of the concave 7 is provided with a cylindrical outer surface which is engaged by the lower ring 28, while the upper concave portion has an integral flange 29 provided with a cylindrical inner surface engaging the upper ring 27; and a segmental wedge 30 is disposed within the annular enclosure afforded by the rings 27, 28 and engages the screw threads 26 and the external tapered surface 31 of the concave 7. Each segment of the wedge 30 is provided with projections 32 engaging sockets in the concave 7, and these segments are also engaged by locking jack screws 33 having screw thread coaction with the concave 7 and with lock nuts 34, and the top of the concave 7 may be manually rotated by means of projections 35 to effect rotation of the

concave and wedge assembly when the jack screws 33 have been released, so as to permit vertical adjustment of the concave 7 and liner 8 relative to the head 4 and mantle 8.

The concave supporting element 25 has a lower outwardly projecting flange 36 provided with an annular concavity 37 which seats directly upon, an upwardly convex annular flange 38 formed integral with the main frame 18. The upper plane surface of the element flange 36 is engaged by a ring 39, and the supporting element 25 is normally held in contact with the frame flange 38 by means of special safety washers 40 coacting with nuts 41 which in turn coat with studs 42 secured directly to the main frame 18. The crusher may be provided with any desired number of studs 42, nuts 41 and washers 40 disposed in an annular series about the ring 39, and the washers 40 are of sufficient strength to normally resist breakage and to permit frictionally restrained rotation of the concave 7 and its support relative to the main frame 18, but are also formed so as to break under abnormal stress whereby the concave 7 may tilt away from the head 4 thus avoiding possible damage to other more important parts of the machine. Such abnormal stresses may be caused by a large piece of tramp iron thrown into the crushing chamber 8, or by accumulation of sticky material within the crushing zone. The washers 40 may be formed of cast iron or other metal suitable for the intended purpose, and are preferably formed as shown in order to provide a section which will break under a predetermined load.

The main frame 18 is provided with a lower bearing 43 and the member 12 has an upper aligned bearing 44, both of which are concentric with the central axis of the concave 7. The eccentric 11 has cylindrical outer lower and upper surfaces coacting respectively with the bearings 43, 44, and also has a lower bearing plate 45 secured thereto by screws 46 and cooperating with a thrust bearing 47 detachably secured to the lower end of the frame 18. The eccentric 11 is adapted to be rotated within the bearings 43, 44 by means of a bevel gear 48 keyed to the medial portion thereof, and this gear 48 meshes with a bevel pinion 49 both of which are enclosed within a chamber 50 formed in the frame 18. The pinion 49 is keyed to one end of a driving shaft 51, the opposite end of which is provided with a pulley 52, and which is journaled in roller bearings 53 carried by a sleeve support 54 detachably secured to the main frame 18. The lower cylindrical portion of the head positioning shaft 5 coacts with an eccentric bore or bearing 55 of the eccentric 11, and as previously indicated, the head 4 rests upon the bearing surfaces 19, 20 coacting with the bearing member 12. With this assemblage, the head 4, shaft 5 and mantle 8, are free to rotate as a unit relative to the eccentric 11, but are gyroscopic relative to the concave 7 and liner 8 during rotation of the eccentric 11 by the gear 48 and pinion 49.

As clearly illustrated in Fig. 2 the center of the lower bearing plate 45 is provided with an elongated substantially rectangular through opening 56 within which is located a driving head 57 secured to the shaft 58 of an oil pump 59. The pump 59 is of the rotary type, and has its inlet 70 communicating with a source of oil supply, while its discharge is in open communication with the opening 56 and the bearing surfaces which are exposed to this opening. Since the lower plate 45 is secured to and is rotatable with the eccentric 11,

11, this plate 45 will engage the driving head 51 and will rotate the pump 59 during normal operation of the crusher, thereby causing the pump to constantly deliver abundant quantities of oil 5 to the lower end of the eccentric 11 and shaft 5 when the machine is running. The thrust bearing 47 is of usual construction, preferably having outwardly directed grooves for conducting oil thereover, and the narrow side of the lower portion 10 of the eccentric 11 is flattened as shown, to provide an oil riser groove 60 extending along the lower bearing 43 but closed at the top. This groove 60 will permit an abundant quantity of oil delivered from the thrust bearing 47, to flow to the bearing 43, without permitting this oil to escape freely from the top of the groove 60 to the gear chamber 50. The inner eccentric bearing 55 is provided with another riser groove 61 extending from the bottom to the top of the eccentric 20 11, this groove serving to supply abundant lubrication for the bearing 55 and being open at the top. The top of the eccentric 11 is in open communication with the upper end of another groove 62 extending throughout the entire length 25 of the bearing 44 and communicating at its lower end with the gear chamber 50 in such manner that the oil delivered from the groove 62 will flood the gear 48 and the pinion 49. Outwardly extending oil grooves may also be provided at the 30 head bearing surface 19; and the annular lip 63 formed at the off-set between the surfaces 19, 20, serves as an oil thrower for slinging excess oil from the surface 19 against the inner annular surface of the supporting member 12 from whence this oil is drained by gravity through 35 openings 64 into the gear chamber 50. A flexible sealing ring 65 is interposed between the member 12 and the surface 20, and a slight amount of the oil delivered from the lip 63 may be supplied to this ring 65 by capillary attraction through wicks 66. The oil from within the chamber 50, after lubricating the gears, as well as other oil from the roller bearings 53, is discharged through an opening 67 to the source of supply for the pump 59.

40 Although the normal operation of the improved gyratory crusher should be apparent from the foregoing detailed description, a resume of such operation may be desirable.

45 The material to be reduced is admitted into the hopper wall 23 and drops by gravity directly into the annular crushing chamber 9 without necessitating the use of feed controls associated with the crushing head. The concave 7 is normally fixed relative to the main frame 10, and the head 4 is being gyrated relative to the concave by the revolving eccentric 11, the head 4 being free to rotate however about the central axis of the main shaft 5 and relative to the eccentric 11. As the pieces of material advance by gravity along the 50 downwardly and outwardly flaring crushing chamber 9, they are intermittently crushed between the rapidly approaching and receding crushing surfaces of the mantle 6 and liner 8, and the resulting fragments constantly gravitate 55 toward the lower discharge opening of the crushing zone, being further reduced during such advancement until they are of a size sufficiently small to pass through the portion of the discharge opening having minimum width. Due to the peculiar formation and relative disposition of the 60 crushing surfaces of the head mantle and concave liner, the pieces of material will be subjected to several successive crushing impulses of about the same intensity and magnitude just prior to 65 the final discharge thereof, thereby minimizing dis-

charge of oversized particles. The final product is delivered from the crushing zone by gravity through the annular space 24 in the main frame.

70 In order to definitely predetermine the size of the final product, the width of the discharge opening at the lower end of the chamber 9 may be varied by vertically adjusting the concave 7. When it is desired to make such adjustment, the segmental wedge 30 must be released by loosening the locking nuts 34 and the jack screws 33, 75 whereupon the concave 7 together with the parts coacting therewith, may be rotated relative to the supporting ring 25. Such rotation of the concave 7 is transmitted through the projections 32 to the segmental wedge 30, causing this wedge 15 to travel along the internal screw threads 26 of the concave support 25. During such vertical adjustment of the concave 7, the sealing rings 27, 28 slide along the adjacent cylindrical surfaces of the concave and thus constantly maintain the 20 wedge 30 inclosed. When satisfactory adjustment has been effected, the jack screws 33 may again be manipulated and locked in place to thereby positively lock the wedge 30 and the concave 7 in adjusted position.

25 Quite frequently, uncrushable material such as a large piece of steel or substance which tends to pack locally within the crushing zone, is admitted to the chamber 9, and unless provision is made for permitting such uncrushable material 30 to pass through the crushing zone, considerable damage may be done. If such uncrushable material is admitted to the improved crusher, and the crushing stresses become excessive, one or more of the safety washers 40 may break. Breakage of one or more of these washers will allow the concave supporting ring 25 to move away from the frame flange 38, thus immediately enlarging the discharge opening from the chamber 9 to a sufficient extent to permit the uncrushable 35 obstruction to pass. Such breakage of the washers 40 will occur only in the event that the crushing stresses become excessively great.

40 The pump 59 which is driven directly from the eccentric will be constantly operated during normal operation of the crusher, as previously explained, and oil will be constantly supplied in abundant quantities to the thrust bearing 47 and to the large opening 56. The oil delivered from the thrust bearing 47 will flow through 45 the groove 60 and will lubricate the lower outer bearing 43. Due to the fact that the upper end of the groove 60 is closed or restricted, the oil surrounding the thrust bearing 47 will be subjected to pressure sufficient to cause the same 50 to flow through the groove 61 and thereby effectively lubricate the bearing 55. The excess oil flowing from the open top of the groove 61 will pass along the surface 19 and through the groove 62 and will thereby effectively lubricate the bearing 44 and the head supporting 55 surface. The oil flowing from the lip 63 and delivered over the wicks 66 will insure abundant oiling of the sealing ring 65 and the excess oil passing through the opening 64 together with that delivered from the groove 62, will insure 60 abundant lubrication of the gear 48 and pinion 49. All of the bearings are thus automatically 65 and effectively lubricated, as well as being protected against ingress of dust and other foreign matter.

70 The improved head mantle attachment comprising the nut 15 of special construction co-acting with the filling metal 18, provides a rigid and durable fastening for normally securing 75

the mantle 6 to the head 4, while permitting replacement of the mantle 6 with minimum effort and loss of time. The improved concave liner attachment comprising the lugs 21 insertable through the slots 14 and cooperable with the lugs 12, also provides a rigid and durable fastening for normally attaching the liner 8 to the concave 7, while likewise permitting convenient replacement of the liner 8 with ease and with minimum loss of time.

From the foregoing description it will be apparent that the present invention provides an improved gyratory crusher structure which is simple, compact and durable in construction, which is abundantly lubricated, which may be conveniently adjusted and repaired, and which is protected against possible damage due to introduction of uncrushable material. The adjusting mechanism is effectively concealed and protects against entry of dirt, while being at all times freely accessible for manipulation. The improved safety washers 60 provide simple concave retaining means and eliminate necessity of running complicated springs for normally holding the concave in place, while at the same time serving to prevent possible breakage of complicated controls in case abnormal conditions of operation are introduced. The sealing ring 66 prevents entry of dust to the lubricating passages and bearings as well as to the bearings, thereby insuring clean oil at all times. The various lubricating passages and conduits furthermore insure an abundant supply of oil to all

bearing surfaces, and the entire assemblage may be readily assembled or dismantled, or opened for inspection of parts.

It should be understood that it is not desired to limit the present invention to the exact details of construction and to the precise mode of operation herein shown and described, for various modifications within the scope of the claim may occur to persons skilled in the art.

I claim:

In a crusher, a crushing head, a normally non-concave coating with said head to form a crushing chamber, a stationary frame having an outer flange, an eccentric for gyrating said head relative to said concave, an annular supporting member for said concave having an outwardly directed flange resting upon said frame, said frame provided with an upper surface, a ring element coating with said upper surface of said supporting member flange, a series of studs secured to said frame and passing through said ring element, and a series of breakable washers interposed between said studs and said ring element, said washers having medial portions bridged outwardly away from the adjacent studs and normally removably urging said ring element in contact with said supporting member flange, and said medial portions being formed to break and to permit free movement of said concave along said studs and away from said frame under abnormal conditions of operation.

HARVEY H. RUMPF.
